INSULATING COVER

Walter W. Urmetz, Parma, Ohio, assignor to Oglebay
Norton Company, Cleveland, Ohio, a corporation of
Delaware

Application May 2, 1956, Serial No. 582,102

6 Claims. (Cl. 22—147)

This invention relates to improvements in coverings that are used with solidifying metal castings, particularly ingots and ingot sinkheads.

It is common practice in the production of killed steel ingots to place a hot top on each ingot mold, to pour molten steel into the mold and hot top to a specified height in the hot top, and to deposit some loose granular or powdery material on the exposed surface of the molten ingot to minimize heat losses from this surface. These materials can be either insulating or exothermic in nature, or a combination of both.

The hot top functions as a source of molten metal for the solidifying ingot, in which a decrease in volume or shrinkage occurs upon freezing of the molten steel. A hot top has limited efficiency, so that upon final solidification of the ingot, there is remnant metal in the hot top which cannot be put into salable product.

If no covering was placed on the exposed molten surface in the hot top, a greater amount of metal would freeze and remain in the hot top. Therefore, a covering is applied to the molten surface to conserve molten steel and the more efficient the covering becomes, the less steel is required to be poured into the hot top to provide a sound ingot and maximum of product.

One of the objects of the present invention is to provide a more efficient covering than is used today and thereby put a greater percentage of the ingot weight into sound product.

A further object of the invention is to provide a packaged covering which will insure measured amounts of insulating and exothermic materials being used on each ingot. Present practice of throwing loose, granular or powdery materials on the ingot depends on the attitude of an unskilled workman and results in irregular amounts being applied to ingots in a heat with consequent loss of product. Another object of the invention provides that in the production of killed steel ingots, covering of the molten steel surface of the ingot is accomplished with a package which disintegrates to successively deposit a definite quantity of exothermic compound on the molten metal, and also provides a divider or diaphragm surrounding the exothermic layer which will not collapse as the molten metal level drops during the contraction of the solidifying ingot, said diaphragm supporting a layer of highly insulating, but not self-supporting material.

A further object of this invention is to provide an insulated diaphragm across the top of the ingot to prevent circulating air currents from carrying away heat from the molten metal as it feeds downward and creates a cavity in the hot top metal.

Reference should be had to the accompanying drawings forming part of this specification in which:

Fig. 1 shows in sectional elevation a portion of an ingot mold with a hot top associated with the upper end of the mold, the mold and hot top having had molten metal poured therein, and a cover embodying the invention herein, supported upon the top of the ingot.

2

Fig. 2 is a sectional elevation similar to Fig. 1 and showing the position of the different components of the cover after the box or housing of the cover has been consumed.

5 Fig. 3 is a perspective view showing a form which the cover will assume.

Fig. 4 is a fragmentary section on the line 4—4 of Fig. 3; and

Fig. 5 is a sectional elevation similar to Figs. 1 and 10 2, showing the position of the elements of the cover at some instant during solidification of the ingot.

The cover per se, comprises a box 1 made up of a rigid or self-sustaining combustible material having bottom and side walls 1a and 1b, and a flap closure which is 15 formed in two portions 2 and 2a, these portions being preferably joined with the end wall of the container or box and being folded over into the position which is shown in Fig. 3, when the contents of the box have been placed therein.

20 Within the lower portion of the box is placed a desired quantity of exothermic compound 3. Suitable exothermic compounds are well known in the art and no particular description thereof need be given. Over the exothermic compound 3 is placed a rigid partition or divider 10, which 25 assumes the form of a plate and may be of thin steel sheet or may be of ceramic material or any other composition that will not collapse at the temperature to which the plate will be subjected in use. The divider or plate 10 engages the sides of the box 1, which box may be provided with a shelf incorporated into the side walls 1b to receive the divider 10.

Above the divider 10 is a body of insulating material 35 evenly distributed over the same. The insulating material 5 may be asbestos fiber, asbestos board, Sil-O-Cel, insulating grog, or any suitable material for the intended use. When the desired quantity of exothermic material 3 has been placed in the box and the divider 10 placed over the exothermic material and the insulating materials placed on top of the plate, then the flaps 2 and 2a of the box 1 are closed and sealed producing a package, and which can be shipped with minimum of contamination or breakage and which is easily handled when the cover is placed upon the molten metal surface.

40 By pressing inward either or both of perforated tabs 6 or 6a, a long handle can be slipped under the flaps 2 or 2a and the cover reached over and released into a hot top which has been filled with molten steel. Alternatively, the tabs may be on the side walls of the cover, as the one shown at 6'.

Upon contact with the molten steel the combustible box 1 will burn instantaneously and release the exothermic material 3 onto the molten metal surface. This material ignites and reacts to generate heat which prolongs liquidity of the molten steel in the hot top. The divider 10 becomes a diaphragm or cap whose edges rest upon the rim of solidified metal frozen against the inner surfaces of the hot top as is shown in Fig. 2. Divider 10, as a cap, is heated to a very high temperature and would radiate much heat to the atmosphere above the cover, if it was not for a layer of insulating material 5 resting upon it. As molten steel in the mold solidifies, a contraction of volume or shrinkage occurs, molten steel feeds downwardly from the hot top to satisfy this shrinkage, and the molten level in the hot top drops.

65 With the usual granular or powdery covering materials of the present art, the lowering of the molten level in the hot top would be accompanied by descent of the covering material. This condition would expose the frozen sidewalls of the forming sinkhead to radiate heat to the atmosphere and allow convection currents of cold air to enter the cavity and carry away more heat.

3

In this invention, the reaction products of the exothermic compound ride the lowering level of the molten metal as an intermediate insulation between the molten metal and the cap formed by divider 10. The latter plus its insulating layer 5 prevent convection currents and minimizes radiation losses from the molten pool and the solidified shell 7a as shown in Fig. 5.

The use of the insulating cover herein described, minimizes heat losses through the open end of the hot top, and reduces the amount of molten steel needed in the hot top to produce a sound ingot.

Customarily, the amount of molten steel poured into a hot top is 15 to 20 percent of the total poured into both mold and hot top. The amount of molten steel fed out of the hot top into the solidified ingot is 3 to 5 percent of the total metal poured into the mold and hot top. This is always needed to produce sound ingot and minimum amount sound product rolled from the ingot.

The difference between the 15 to 20 percent and the 3 to 5 percent is that amount of molten steel wasted by the inefficiency of the hot top in making available the 3 to 5 percent. This inefficiency is inherent and is attributed to the heat capacity and conductivity, of the hot top mass, and heat loss through the top end of the hot top.

For a fixed hot top construction only, the heat loss through the top end can be minimized, and the insulating cover herein described reduces such losses markedly as is shown by results obtained by plant trials.

A certain hot top and mold combination covered with a proprietary exothermic covering produced an 8380 pound ingot, of which 7120 pounds of molten steel were in the mold and 1260 pounds in the hot top. This latter was 15 percent of the total ingot.

The same hot top and mold combination requiring 7120 pounds of molten steel in the mold, only required 1060 pounds of molten steel in the hot top (13 percent of the total ingot) when covered with the insulating cover herein described. A savings of 200 pounds of steel per ingot was made. For this particular practice, the open hearth furnace produced 41 ingots with the conventional cover and 42 ingots with the cover of this invention.

The increase in productivity did not require additional melting capacity. Uniform covering practice was obtained. A cleaner operation resulted. Human judgment as to how much, and how well distributed would be a loose material thrown on an ingot would be eliminated in favor of measured amounts positively emplaced.

Having thus described my invention, I claim:

1. A heat retaining unit for use as a cover in the open upper end of a mold or hot top in which molten metal is cast comprising a layer of predetermined thickness of loose exothermic material, a rigid non-combustible divider plate separate from said layer of exothermic material and overlying the latter, a layer of predetermined thickness

of loose insulating material separate from but overlying said divider plate, and combustible container means for said layers and said divider plate whereby when said unit is used said container means is destroyed by combustion and said exothermic material falls onto the molten metal and into the shrinkage cavity that forms as the molten metal cools while said divider plate bridges the shrinkage cavity and supports the layer of loose insulating material above said cavity and above the upper end of the cooling metal in the mold or hot top.

2. A heat retaining unit for use in the open upper end of a mold or hot top in which molten metal is cast comprising a heat destructive box of a size and shape to substantially interfit the said open upper end of the mold or hot top and engage the upper exposed surface of the molten metal therein, a layer of predetermined thickness of loose exothermic material in said box covering the bottom thereof, a rigid non-combustible divider plate interfitting the interior of said box and separate from said layer of exothermic material and overlying the latter, and a layer of predetermined thickness of loose insulating material in said box separate from but covering and supported by said divider plate whereby when said unit is used said box is destroyed by combustion and said exothermic material falls onto the molten metal and into the shrinkage cavity that forms as the molten metal cools while said divider plate bridges the shrinkage cavity and supports the layer of loose insulating material above said cavity and above the upper end of the cooling molten metal in the mold or hot top.

3. A heat retaining unit as defined in claim 2 and wherein said box is provided with closure flaps covering the layer of loose insulating material whereby the contents of said box are protected and the unit can be handled effectively during shipping and storage and use with minimum of likelihood of damage thereto.

4. A heat retaining unit as defined in claim 2 and wherein said divider plate is of thin sheet metal.

5. A heat retaining unit as defined in claim 2 and wherein said divider plate is a ceramic plate.

6. A heat retaining unit as defined in claim 3 and wherein said box is provided with displaceable tabs for the connection of a handling tool to said unit to facilitate its placement on top of the molten metal in the mold or hot top.
